US00D826900S

(12) **United States Design Patent** (10) **Patent No.:** **US D826,900 S**
(45) **Date of Patent:** **** Aug. 28, 2018**

(54) **HEADSET**

(71) Applicant: **XTRFY GAMING AB**, Landskrona (SE)

(72) Inventors: **Erik Jensen**, Dalby (SE); **Joakim Jansson**, Billeberga (SE); **Kristopher Brogren**, Helsingborg (SE)

(73) Assignee: **XTRFY GAMING AB**, Landskrona (SE)

(**) Term: **15 Years**

(21) Appl. No.: **35/503,382**

(22) Filed: **Jun. 12, 2017**

(80) **Hague Agreement Data**

Int. Filing Date: **Jun. 12, 2017**

Int. Reg. No.: **DM/096799**

Int. Reg. Date: **Jun. 12, 2017**

Int. Reg. Pub. Date: **Jul. 21, 2017**

(30) **Foreign Application Priority Data**

May 29, 2017 (EM) 004022424-0001

(51) **LOC (11) Cl.** **14-01**

(52) **U.S. Cl.**

USPC **D14/206**

(58) **Field of Classification Search**

USPC D14/205–206, 223, 225, 226, 372, 433; D29/112; D24/173–174
